UNITED STATES PATENT OFFICE

114,487

DESIGN FOR AN OPHTHALMIC INSTRUMENT

William F. Peck, Kenmore, N. Y., assignor to
American Optical Company, Southbridge,
Mass., a voluntary association of Massachu-
sets

Application September 16, 1938, Serial No. 79,946

Term of patent 14 years

To all whom it may concern:

Be it known that I, William F. Peck, a citizen
of the United States of America, residing at
Kenmore, in the county of Erie and State of New
York, have invented a new, original, and orna-
mental Design for an Ophthalmic Instrument, of
which the following is a specification, reference
being made to the accompanying drawings, form-
ing a part thereof.

Fig. I is a face view of an ophthalmic instru-
ment embodying my new design.

Fig. II is a similar view of the opposed side
of the instrument.

Fig. III is a top plan view of the instrument;
and

Fig. IV is an end view of the instrument.

I claim:

The ornamental design for an ophthalmic in-
strument, substantially as shown.

WILLIAM F. PECK.
